PUMP

Arthur J. Penick and Kirby T. Penick,
Houston, Tex.

Application January 24, 1933, Serial No. 653,302

2 Claims. (Cl. 103—44)

This invention relates to a pump.

The invention has particular relation to a pump specially designed for use in pumping gritty fluid, such as "slush".

- 5 An object of the invention is to provide a pump of the character described which includes cylinders and reciprocating plungers therein and wherein provision is made for excluding the pumped fluid from the cylinders and plungers
 10 to the end that these relatively reciprocable parts will not be worn or cut away by the gritty fluid.
 Another object of the invention is to provide a pump of the character described adapted to utilize a clean operating fluid which is separated
 15 from the fluid being pumped by reciprocable pistons which are actuated by the plungers by means of said operating fluid.
 Another object of the invention is to provide, in a pump of the character described, novel
 20 means for packing the plungers.

With the above and other objects in view the invention has particular relation to certain novel features of construction, operation and arrangement of parts, an example of which is given in
 25 this specification and illustrated in the accompanying drawings wherein:

Figure 1 shows a plan view of the pump partly broken away.

Figure 2 shows a longitudinal sectional view
 30 taken on the line 2—2 of Figure 1.

Figure 3 shows a fragmentary cross sectional view taken on the line 3—3 of Figure 1.

Figure 4 shows a sectional view taken on the line 4—4 of Figure 3, and

35 Figure 5 shows a side view, partly in cross section taken on the line 5—5 of Figure 2.

Referring now more particularly to the drawings, wherein like numerals of reference designate similar parts in each of the figures, the
 40 numeral 1 designates the pump casing as a whole which is provided with an inlet chamber 2 the intermediate valve chambers 3, 3 and the discharge chamber 4. The intermediate valve chambers are separated by suitable partitions 5.
 45 Entering the inlet chamber 2 there is an inlet line 6 and leading out from a discharge chamber 4 there is the discharge line 7.

Incorporated into the pump casing, beneath
 50 the inlet chamber 2 are the cylinders 8, 8 in each of which there is mounted to reciprocate a plunger 9. Each plunger is of a hollow cylindrical form open at its forward end and closed at its other end and attached to this last mentioned end there is a plunger rod 10. These plunger rods 10 work through suitable stuffing

boxes 11 in the end plates 12 which are secured to and close the corresponding ends of said cylinders.

Around each plunger 9 there is a packing sleeve 13, formed of suitable packing material and which is confined between the retaining rings 14, 14. One of these rings abuts the annular inside shoulder 15 of the corresponding cylinder and the other ring is retained in place by the cylindrical open work cage 16 which surrounds the open end of the plunger and whose outer end is provided with a central socket 17. The corresponding end of each cylinder has the end-plate 18 bolted thereon. Each endplate 18 has an internally threaded tubular extension 19 into which the rod anchor 20 is threaded. The inner end of this anchor terminates in a rod 21 whose inner end works in the corresponding socket 17 and surrounding said rod and interposed between the anchor 20 and the corresponding cage 16 there is a strong coil spring 22 whereby said cage is held in yielding contact with the opposing ring 14. The anchors 20 may be adjusted, as is obvious to secure the proper compression on the corresponding packing sleeve 13. Around each rod anchor 20 within the corresponding extension 19 there is a packing 23 which is retained in place by the gland 24 which is screwed in said extension and locked therein by means of the corresponding lock nut 25.

Each packing sleeve 13 is provided with an annular groove 26 in each end thereof forming pockets and there are the channels 27 leading through the retainer rings 14 through which the operating fluid may enter said pockets and when under pressure this operating fluid will hold the lips forming the outer sides of said pockets closely against the cylinder walls to prevent leakage past the packing sleeves 13.

The transverse partition 28, separating the inlet chamber 2 from the valve chambers 3, has the valve seats 29 and cooperating with these seats are the upwardly opening inlet valves 30. In the top of the pump casing above said valves are the removable caps 31 having the sockets 32 forming guides for the valve stems 33 and surrounding these stems and interposed between said valves and caps are the coil springs 34.

The valve chambers 3 communicate with the discharge chamber 4 through the valve seats 35 which are controlled by the outwardly opening valves 36. Above these valves are the detachable caps 37 closing the top of the pump casing and having the sockets 38 in the underside thereof forming guides for the stems 39 of the valves 36.

Interposed between the caps 37 and valves 36 are the coil springs 40 which normally hold said valves closed. The caps 31, 37 respectively are held in place by the corresponding yokes 41, 42, 5 which are suitably bolted to the top of the pump casing and whose ends are downwardly turned and rest against said respective caps.

On opposite sides of the pump are the respective pairs of vertically disposed cylinders 43, 43, 10 44, 44 whose lower ends are connected into the respective cylinders 8 by means of the front and rear channels 45, 46 respectively and the upper ends of these respective pairs of vertical cylinders are connected into the valve chamber 3 by means 15 of the channels 47, 48 respectively.

In the vertical cylinders 43, 44, are suitable liners as 49 and these liners are retained in place by means of the open work cages 50 which rest against the upper ends of said liners and which 20 in turn are held in place by corresponding set bolts 51 which are threaded through the heads of said cylinders. The liners 49 have the external shoulders 52 arranged opposite the inside shoulders 53 in the corresponding cylinders and a suitable 25 packing ring 54 surrounds each liner and is clamped between said shoulders. In each liner 49 there is a piston 55 whose ends are preferably cup shaped and these plungers are freely movable from end to end of their corresponding liners. 30 Fastened in the ends of said liners are the spiders 56, 56, having the central inwardly extending stops 57, 57 which limit the movement of the corresponding plunger. These plungers 55 separate the clean operating fluid from the gritty fluid 35 being pumped and prevent the gritty fluid from reaching the main cylinders 8 and the plungers 9 therein.

Upon forward stroke of a plunger 9, the operating fluid is drawn through the corresponding 40 channel 46 from one side of the corresponding pistons 55, causing a downward movement or suction stroke of said pistons and the fluid to be pumped will accordingly be drawn in through the intake pipe 6 into the chamber 2 lifting the valves 45 30 and passing into the corresponding cylinders 8 and upon back stroke of said plunger 9 the operating fluid will be forced back through the corresponding channel 46 beneath the pistons 55 and these pistons will be forced upwardly forcing the 50 pumped fluid into the corresponding valve chambers 3 lifting the corresponding valve 36 and passing out through the discharge line 7. Upon this back stroke of the plunger 9 the operating

fluid will be drawn through the channel 45 from the corresponding pair of cylinders 8 causing a suction stroke of the corresponding pistons 55 and drawing the pumped fluid in from the chamber 2 through past the corresponding valves 30 and into the corresponding cylinders 43 and upon the next succeeding forward stroke of said plunger 9 the operating fluid will be forced back through the corresponding channel 47 into its valve chamber 3 and thence past the corresponding 10 discharge valve 36 and out through the discharge pipe 7. Thus, upon each stroke of a plunger 9, the pumped fluid will be drawn into one pair of cylinders 43, or 44, and simultaneously discharged from another pair of said cylinders to 15 the end that there will be a constant and approximately uniform volume of fluid discharged from the discharge line 7.

The drawings and description disclose what is 20 now considered to be a preferred form of the invention by way of illustration only, while the broad principle of the invention will be defined by the appended claims.

What we claim is:

1. A pump comprising a casing having an inlet 25 chamber, provided with an inlet, an intermediate chamber and a discharge chamber provided with an outlet, said pump having a valve controlled port connecting said inlet and intermediate chambers and a valve controlled port connecting the intermediate chamber with the discharge chamber and through which chambers and ports the pumped fluid may move from said inlet to said outlet, a pumping cylinder having a removable liner and removable inwardly extended end stops, 30 a piston therein, said pump having a passageway connecting the intermediate chamber with said cylinder, on one side of said piston, an operating cylinder for containing an operating fluid, there 35 being a passageway connecting the operating cylinder with the pumping cylinder, on the other side of the piston and a reciprocable plunger in said operating cylinder.

2. In a pump, a pumping cylinder having an 45 inside abutment, a liner in the cylinder having an external abutment adapted to engage said internal abutment, means for securing said liner in the cylinder, end spiders at the respective ends of the liner having inwardly projecting stops and a piston in the liner whose range of movement is 50 limited by said stops.
